UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WINDOW-CONTROL MECHANISM.

Application filed January 23, 1922. Serial No. 531,041.

To all whom it may concern:

Be it known that I, STANLEY W. NICHOLSON, a citizen of the United States of America, residing at Toledo, in the county of Lucas and State of Ohio, have invented certain new and useful Improvements in Window-Control Mechanism, of which the following is a specification, reference being had therein to the accompanying drawings.

This invention relates to window control mechanism and particularly relates to devices for raising and lowering vehicle windows.

It is the object of the invention to provide a control mechanism for sliding windows comprising a rod extended upon the sliding element of the window in the direction of travel thereof and rotative bodily to control locking of the said element in selective positions of adjustment.

In the drawings:—

Figure 1 is an interior view of an automobile door having a window in its upper portion equipped with the herein described control mechanism.

Figure 2 is a perspective view of the window control rod and the stationary guiding and locking tube.

Figure 3 is a cross section on line 3—3 of Figure 1.

Figure 4 is a fragmentary enlarged view of a portion of Figure 1 disclosing the journal bearing of the control rod upon the sliding closure of the window.

Figure 5 is a sectional view of the same on line 5—5 of Figure 4.

Figure 6 is a vertical cross section on line 6—6 of Figure 4.

In these views the reference character A designates an automobile door having in its upper portion the window opening B and C is a closure for said opening having the nature of a vertically slidable glass plate adapted in lowered position to enter a chamber D formed in the lower portion of said door. The plate C is rigidly engaged at its lower edge by a channel strip E extending preferably the full width of the glass and to one end of said strip there is rigidly secured a bracket F having spaced projecting arms G terminating in vertically aligned journal bearings G', in which is mounted the lower extremity of a rod H, said rod having at its upper end a laterally projecting handle I. By means of said handle the rod H may

be longitudinally stressed to raise or lower the glass plate C. Said rod extends through a tubular casing J rigidly secured to one of the uprights K of the window frame, said casing acting as a guide for the rod and being longitudinally slotted as indicated at L to accommodate the projecting handle member I. Through rotation of the rod H the handle I is adapted to additionally function as a locking member to hold the plate C at any desired elevation, this result being secured by engagement of a rectangular shank portion I' of the handle in any one of a series of notches M formed at suitable space intervals in an edge of the slot L, as is best seen in Figure 2. To positively maintain said handle member in engagement with the desired notch a spring N is associated with the rod H, one end portion of said spring being secured to the rod and forming several coils about the latter and the other end portion forming an arm projecting parallel to the plate C and terminally bearing upon said plate. Thus said spring exerts a rotative effect upon the rod in the direction of the arrow shown in Figure 5 tending to urge the handle toward the notched edge of the casing J. The preferred location for the spring N is intermediate the two journal bearings G' as is best seen in Figure 4. The provision shown in Figures 4 and 5 for securing said spring to the rod H consists in vertically slitting the lower end portion of said rod as indicated at O and terminally bending the spring as indicated at N' to engage in said slit. This engagement of the spring with the rod restrains the latter from downward movement in the bearings G' and upward movement of the rod is prevented by nuts K engaging a threaded portion of the rod below said bearings. The means employed to secure the bracket F to the channel strip E comprises a stud bolt P depending rigidly from said strip and passing through the bracket, nuts P' being engaged with said stud below the bracket to clamp the latter in engagement with the strip. The bracket F may be economically formed from sheet metal bent to an L form as best seen in Figure 6 and having the arms G formed as integral 105 tongues terminally looped to form the split journal bearings G'.

Suitable means may be provided for counterbalancing the sliding plate C as for example the pivotal arm R engaging at its free

end beneath the strip E and upwardly urged by the coiled spring S.

It is preferred to form the casing J of sheet metal with a laterally extended two-ply securing portion J', forming a seat for the channel element J² in which the plate C slides, one or more screws J³ being employed to attach the portion J² to the upright K.

In the use of the described device, raising or lowering of the plate C is accomplished by first rocking the handle I toward said plate to disengage said handle from the notched edge of the casing J. An upward or downward stress is then exerted upon the rod H through said handle to shift the plate C to the desired elevation. Through extending said rod into proximity to the top of the plate C the handle I is rendered accessible in all positions of the sliding plate.

20 It is to be noted that a variety of functions is derived from the rod H. Thus said rod establishes a connection between the locking handle I and the lower portion of the plate C to hold said plate normally stationary. Furthermore said rod transmits to the window member from the handle I the stress applied to raise or lower said rod. Also said rod transmits to the handle member I the rotative effort of the spring N whereby said handle is urged into normal engagement with the notched edge of the casing J.

What I claim as my invention is:—

1. In a window control mechanism, a 35 slideable window member, a chamber receiving said member in the open position thereof, a rod mounted upon said member extending in the direction of movement thereof, and a journal bearing carried by said member, the 40 rod being rotative in said bearing to additionally control locking of said member, and having a portion accessible within said opening in all positions of the sliding member.

2. In a window control mechanism, a 45 slideable window member, a chamber receiving said member in the open position thereof, a rod carried by said member and forming a control element therefor, a locking member fast upon said rod, functioning also as a 50 control handle for the rod, a journal bearing carried by the window member, and rotatively engaged by the rod, and a stationary locking member engageable by the first mentioned locking member through rotation of 55 said rod, and having a portion accessible within said opening in all positions of the sliding member.

3. In a window control mechanism, a 60 slideable window member, a chamber receiving said member in the open position thereof, an adjacent stationary locking member elongated in the direction of travel of said window member, a rod carried by the window member parallel to said locking member, a journal bearing upon the window

member rotatively engaged by said rod, and a locking member fixed upon said rod normally engaging said stationary locking member and releasable through rotation of said rod, said rod having a portion accessible 70 within said opening in all positions of the sliding member.

4. In a window control mechanism, a vertically slideable window member, a substantially vertical rod mounted upon the window member, a journal bearing secured to the window member adjacent the lower edge thereof, and rotatively engaged by said rod, the upper end of the rod being free, a locking member fast upon the upper end portion 75 of said rod, and a coacting stationary locking member engageable in various positions of the window member by the first mentioned locking member through rotation of said rod.

5. In a window control mechanism, a slideable window member, a locking member extending adjacent said window member in the direction of travel thereof, a rod rotatively mounted upon the window member 90 parallel to said locking member, a spring engaging one extremity of said rod exerting a rotative effort thereupon, and a locking member carried by the other end portion of the rod, urged by said spring into engagement with the first mentioned locking member.

6. In a window control mechanism, a vertically slideable window member, a rod vertically carried by said window member, a 100 pair of spaced journal bearings secured to the lower extremity of said window member, and rotatively mounting said rod, a spring arranged between said bearings and exerting a rotative effort upon the rod, and a locking element carried by the upper end portion of the rod.

7. In a window control mechanism, a vertically slideable window member, a substantially vertical rod journaled substantially at 110 its lower end upon the lower portion of said window member, a stationary latch member, a combined control handle and latch member fixed upon the upper portion of said rod and engageable with the stationary latch member upon rotation of the rod, and spring means acting to rotate the rod to maintain said latch members normally engaged.

8. In a window control mechanism, the combination with a vertically slideable window member, of a substantially vertical rod journaled substantially at its lower end upon said window member, a spring engaging the lower end portion of said rod and rotatively stressing said rod, a stationary latch member, and a latch member upon the upper portion of said rod normally engaged by said spring with said stationary latch member.

9. In a window control mechanism, a slide-

- able window member, a rod mounted upon said member and extending in the direction of movement thereof forming a control element for the window member, a latch member mounted upon said rod, and a tubular sheet metal latch member housing said rod coacting with the latch member thereon, said tubular member having a lateral extension for positioning the same.
10. In a window control mechanism, a 5 slideable window member, a runway therefor, a control rod for said member extending thereupon in the direction of travel thereof, a latch member upon said control rod, and a coacting tubular latch member inclosing said rod and having an extension providing a seat for said runway.
11. In a window control mechanism, a 10 slideable window member, a rod mounted upon said member, and bodily rotative to control locking of said member, and a journal bearing for said rod carried by said member, and means resiliently urging said rod rotatively to locking position.
12. In a window control mechanism, a 15 slideable window member, a rod mounted upon said member affording control of the sliding of said member and bodily ro-
- tative to control locking of said member, and a journal bearing for said rod carried by said member, and means resiliently urging said rod rotatively to locking position.
13. In a window control mechanism, a 20 slideable window member, a control rod for said member carried thereby extending in the direction of travel thereof, and a relatively stationary tubular guide member for said rod formed of sheet metal and provided with a return bent lateral extension.
14. In a window control mechanism, a 25 slideable window member, a chamber receiving said member in open position thereof, a rod extended upon said window member substantially in the direction of travel thereof and journaled upon the edge portion of the window member nearest adjacent said chamber, a stationary latch member, a coacting latch member fixed upon said rod and engageable with the stationary latch member upon rotation of the rod, and spring 30 means acting to rotate the rod to maintain said latch members normally engaged.

In testimony whereof I affix my signature.

STANLEY W. NICHOLSON.
